[57] CLAIM

The ornamental design for a miniaturized basketball
backboard, as shown and described.

DESCRIPTION

FIG. 1 is a front elevational view of a miniaturized basketball backboard showing my new design;
FIG. 2 is a left side elevational view thereof, the right
side elevational view being a mirror image thereof;
FIG. 3 is a top plan view thereof;
FIG. 4 is a bottom plan view thereof; and
FIG. 5 is a rear elevational view thereof.

FIG. 1

FIG. 2

FIG. 3

FIG. 5

FIG. 4
